UNITED STATES PATENT OFFICE.

EDWARD I. PARSONS, OF SAN FRANCISCO, CALIFORNIA, ASSIGNOR TO THE AMERICAN STEEL AND WIRE COMPANY, OF CHICAGO, ILLINOIS.

MANUFACTURE OF FLAT WIRE CABLE.

SPECIFICATION forming part of Letters Patent No. 658,118, dated September 18, 1900.

Application filed January 2, 1900. Serial No. 48. (No model.)

To all whom it may concern:

Be it known that I, EDWARD I. PARSONS, a citizen of the United States, residing in the city and county of San Francisco, State of California, have invented an Improvement in the Manufacture of Flat Wire Cable; and I hereby declare the following to be a full, clear, and exact description of the same.

My invention relates to an apparatus to be used in the manufacture of flat wire cables such as are formed by laying a series of ropes side by side and securing them together by wire stitching to form a flat cable of any desired width, which is especially useful in mining work and for hoisting purposes. In the manufacture of this class of cables it is customary to lay up a series of wire ropes of any suitable or desired size, said ropes being laid side by side until a cable of desired width can be made therefrom. These ropes are then stitched through from one side to the other and bound together by wires passed through the strands of said rope by suitable needles, the rope being thus sewed backward and forward until it is completed. A difficulty arises in the manufacture of this rope on account of the unequal tension brought upon these sewing-wires by reason of the different power applied by the operators in pulling the wires through. The result is that when the cable is subjected to the strain of its work, such as hoisting heavy cages in mining-shafts, it is apt to be drawn or stretched and the edges unequally elongated, and this prevents the cable from hanging and winding evenly upon its winding-drums.

It is the object of my invention to overcome this difficulty, which I do by providing a tension device to be connected with the stitching or sewing wires, so that when they are pulled through from opposite sides and by different men they will all be subjected to practically the same tension, thus making an evenly-constructed flat cable.

My invention consists of a hook or equivalent device to which the sewing-wires are connected, and springs and disengaging latches are so arranged with relation to these parts that when a certain determined tension has been brought upon the sewing-wires the

latches will be disengaged and release the pull upon the sewing-wires.

My invention also comprises details of construction, which will be more fully explained by reference to the accompanying drawings, 55 in which—

Figs. 1 and 4 are general views of the device, Fig. 1 showing parts in section, and Fig. 4 showing parts in perspective and with the spring 3 broken away. Fig. 2 is an end view 60 of the same. Fig. 3 is a top view showing the use of an elongating spring. Fig. 5 is a side view of Fig. 3.

The frame consists of a disk A, to which the handle B is fixed. From this disk A rods a 65 extend through disk C and disk D. The disk C slides upon the rods a, while the other ends of the rods are fixed to the disk D, and between these two disks the spring 3 plays.

2 is a forked bar, carrying in its forked end 70 the bar 7, which is guided in the fork by slots 14, having the pins E entering the same. This bar 7 terminates in a hook 13, and this hook takes hold of the wire with which the ropes are sewed together. The body or shank F of 75 the bar 2 is slidable through the center of disk D, and its outer end is screwed into the disk C, so that by pulling upon the handle B the disk D is caused to slide on part F and against the tension of the spring 3. In the 80 front end of bar 7 is mounted a bell-crank lever 6, one arm being formed into a latch 5 and held down by a spring 8 into engagement with a catch 4, formed in the split portion of bar 2, and so locking the bar 7 to the bar 2. 85 To the other arm of the lever 6 is hinged a rod 9, passing loosely through an eye 10, carried by the disk D. The outer part of rod 9 is screw-threaded and has nuts 12 moving upon it. These nuts are placed in such a position 90 that when pulling upon handle B the disk D is brought toward them, compressing the spring until the eye 10 strikes the nuts 12, consequently pulling upon rod 9 and upon lever 6 until its latch 5 is released from catch 95 4. This unlocks bars 2 and 7 from one another and releases the bar 7, with the hook and wire, and gives notice that a sufficient tension has been brought upon the wire. This tension or pull is produced by its connection with the 100

wire thread by which the ropes forming the cable are sewed together, as follows:

- 13 is a hook formed upon the end of the 5
slidable bar 7, and this hook is connected
with the wire thread. When the latter is
being pulled through the cable, the operation
will be as follows: The strands of the wire
ropes are separated by a suitable tool and the
wire by which the ropes are being sewed to-
gether is passed through these spaces by
means of a suitable needle, and when it has
been passed through all of the ropes which
form the cable passing transversely across
the width of it it is connected with the hook
15 13, and the operator taking hold of the handle
pulls upon it. This pull extends or com-
presses the spring according to the character
of spring used and allows the shank 2 to be
pulled outwardly with relation to the handle
20 and the disk through which the rod 9 slides.
This rod then slides through the disk until
the adjusting-nut or equivalent adjusting de-
vice strikes the eye 10, and pulling upon the
bell-crank lever finally disengages the latch
25 5 and allows the slidable bar upon which the
hook is placed to suddenly slide along the
shank until it is stopped by a pin or the end
of the longitudinal slots, as shown at 14. This
gives warning to the operator that he has
30 pulled upon the wire the exact amount re-
quired to properly draw it through the strands
of the ropes and to produce a certain tension
thereon. The wire being then again passed
through the ropes of the opposite side the
35 other operator will by a similar apparatus pull
upon the wire upon that side, and the next
stitch will be formed with exactly the same
tension as the previous one. This insures the
strain upon the stitching-wires being equal in
40 every case independent of the strength or pull
of the operators, and the stitching being thus
evenly done there will be no danger of the
rope being warped or twisted by use after it
is completed.
- 45 In Figs. 3 and 5 the constructions are sub-
stantially similar to those shown in Figs. 1
and 4 with a modified form of spring 3'. In
Figs. 3 and 5 the pull is a direct one upon the
spring, which takes the frame A along, and
50 with it the eye 10, to affect the rod 9 and to un-
lock the bar 7 from the forked bar 2, as in Figs.
1 and 4. In Fig. 2 the circles W, also shown
in dotted lines in Fig. 1, represent guide-rods
to enable the operator to pull in line with the
55 work to be done and not to one side, which
would bend the wire unnecessarily.

Having thus described my invention, what
I claim as new, and desire to secure by Letters
Patent, is—

1. An apparatus for regulating the pull 60
upon stitching-wires in the manufacture of
flat cable, consisting of a bar having a hook
upon one end through which the pull is ex-
erted, a shank or stem upon which the hook-
bar is slidably guided, said shank having a 65
handle through which the pull thereon is ex-
erted, a yielding spring through which con-
nection is made between the handle and the
shank, a latch mechanism connecting the
hook-bar with the shank, and a device where- 70
by the latch is disengaged when a given ten-
sion has been reached.

2. A tension - regulating device for the
stitching - wire used in the manufacture of
flat cables consisting of a slidable hook-bar 75
through which the pull is exerted, a spring-
pressed latch fulcrumed to said bar, a shank
with relation to which the hook-bar is guided
and slidable, said shank having a catch adapt-
ed to be engaged by the latch of the hook-bar, 80
a spring, a handle connected therewith and
a yoke or frame through which pull upon the
handle is transmitted to the shank and thence
to the hook-bar, and a connection between
the latch and said slidable frame whereby 85
the latch is disengaged and the slidable bar
released when a certain tension has been
reached.

3. A tension-regulating device comprising
a slidable bar having a hook at one end, a 90
spring-pressed latch-lever fulcrumed to the
other, a shank with relation to which the
hook-bar is guided and slidable, said shank
having a catch with which the latch-lever is
adapted to engage, a frame or yoke with re- 95
lation to which the shank and connected
hook-bar are slidable, a spring and a handle
through which pull is exerted thereon and a
rod having one end connected with the latch-
lever and carrying an adjusting nut or like 100
stop with which the frame contacts when the
spring is acted upon by the pull and the re-
quired tension reached whereby the latch is
disengaged and the hook-bar is allowed to
slide upon its guide. 105

In witness whereof I have hereunto set my
hand.

EDWARD I. PARSONS.
